[57] CLAIM

An ornamental design for a conifer forest seedling protector, substantially as shown and described.

DESCRIPTION

FIG. 1 is a perspective view of a conifer forest seedling protector; showing my new design;

FIG. 2 is a front view of the same;

FIG. 3 is a view of the same from the rear;

FIG. 4 is a view looking up from the bottom; and

FIG. 5 is a top view.

FIG. 1

FIG. 2

FIG. 3

FIG. 4

FIG. 5
